Primary Examiner—Elizabeth A Albert*Assistant Examiner*—Kelley A Donnelly(74) Attorney, Agent, or Firm—Kenneth H. Ohriner; Perkins Coie LLP(57) CLAIM

The ornamental design for an umbrella, as shown and described.

DESCRIPTION

FIG. 1 is a perspective view showing my new design.

FIG. 2 is a front view.

FIG. 3 is a back view.

FIG. 4 is a right side view.

FIG. 5 is a left side view.

FIG. 6 is a top view; and,

FIG. 7 is a bottom view.

The broken lines are for the purpose of illustrating the environment of the design only and form no part of the claimed design.
